PACKAGE CARRIER AND CORD CUTTING DEVICE

Joseph Alexander, New York, N. Y.

Application March 29, 1945, Serial No. 585,408

CL. 7-14.1

This invention relates to carrier devices, and more particularly to carriers for packages, parcels, articles and like structures.

It is one of the objects of this invention to provide means for securely engaging the binding strings of packages or articles so as to maintain the latter always in substantially horizontal position.

It is another object of this invention to provide a carrier device adapted to be grasped by the hand of a person carrying the package or article, said carrier device including a centrally located hook member adapted to extend between adjacent fingers of said hand and to engage the string or strings of the package to be carried.

A still further object of this invention is to provide a novel carrier device for packages, parcels and the like, which device includes means for impeding ready disengagement of the hook member from the string or strings of the package, said means taking into consideration various thicknesses of string material employed for tying said package.

Still another object of this invention is to provide means affording swingable or rotatable movement of said hook member with a certain amount of friction so as to bring about an adjusted position of said hook member relatively to the remainder of said carrier device and to avoid unwieldiness when packing and storing a great number of said carrier devices.

It is a further object of this invention to provide means enabling the user to sever at will the string or strings during disengagement of said carrier means from said package, thus facilitating ready unpacking of the package.

Still a further object of this invention is to provide simple, inexpensive and efficient carrier means for packages and the like, which means may be easily manipulated and readily applied to various sizes of packages which may be closed by strings or cords.

Yet, another object of this invention is to provide a carrier device of a simplified construction which may be made of a suitable material, such as plastic, plastic composition, wood or metal, and manufactured in mass production.

These and other objects and advantages will become more apparent from the ensuing description of the invention, and will be further clearly understood by referring to the accompanying drawing.

In the drawing:

Fig. 1 illustrates in perspective a carrier device

as seen in Fig. 2 and as applied to the strings of a package.

Fig. 2 is a front-elevational view of a carrier device embodying the present invention, and as seen in its applied position in Fig. 1.

Fig. 3 is a side-elevational view of the carrier device illustrated in Fig. 2, partly in section, taken along line 3-3 of Fig. 2.

Figs. 4 and 5 show side-elevational views of carrier devices, both in modified form.

Fig. 6 illustrates a carrier device made in accordance with this invention and shown in a still

Fig. 7 is a fragmentary sectional view taken in accordance with this invention and shown in a still further modified form.

15 along line 7—7 of Fig. 6.

Referring now in particular to the drawing, there is shown in Fig. 1 a package 10, the wrapper 11 of which is tied by means of string element 12 in the conventional manner. In order to facilitate carrying of package 10, carrier device 13 is applied for engagement with string 12. Carrier device 13 comprises the handle proper 14 and hook member 15. Hook member 15 has an upper portion 16 which embraces handle 14 in groove 17 which is circular and centrally disposed with respect to elongated handle 14. Hook member 15 may be preferably made from wire material, but may also form a unit with handle 14. In such instance, handle 14 and hook 15 may be made from a single piece of plastic material or plastic composition.

Since groove 17 is of circular shape, hook member 15 can turn with its part 16 about handle 14.

35 From part 16 to hook member proper 15, there
extends a substantially straight portion 18 ter-
minating in loop 19, the free end 20 of which is
turned inwardly and preferably contacts with its
bend 21 said portion 18 at 22. Since the material
of which hook member 15 is manufactured is
40 springy, it will be easily realized that upon slid-
ing of string 12 between bend 21 and portion 18
at 22, loop 19 will give sidewardly and will allow
string 12 to engage the lower end 23 of loop 19.
Bend 21 comes then to lie against portion 18 at
45 22, thus preventing the string from unintentional
disengagement with the hook member 15.

Fig. 3 shows a side-elevational view of hook member 15 on handle 14, hook member 15 being swingable about handle 14 (as indicated by dotted lines) so as to afford adjustment of the position of the package 10 when the same is being carried.

Fig. 4 illustrates an end view of a carrier device 30, shown in modified form, the hook member 31 having a lower loop 32, whose leg portion 33 is

corrugated at 34 and 35 in order to prevent unintentional disengagement of the string or cord from hook member 31, as can be easily seen. The free end 36 of hook member 31 is turned inwardly providing between straight portion 37 and bend 38 an extremely small passageway to further prevent accidental disengagement of the string from carrier hook 31. The remaining part 39 of hook member 31 and the handle 40 are otherwise constructed in a similar manner to the construction shown in Figs. 1 to 3, inclusive.

Fig. 5 shows a further modified form of a carrier device 50 having an elongated hook member 51 whose upper free end 52 springedly contacts straight portion 53 of the hook member, whereas a knee-shaped or corrugated portion 54 positioned substantially intermediate the lower end 55 and bend 56 of hook member 51 leaves a narrow passageway or gap 57 between said knee-shaped portion 54 and the substantially straight hook portion 53.

Figs. 6 and 7 represent another improved and modified form of a carrier device 60, whose hook member 61 terminates into a loop 62 having a bent portion 63 in contact with a substantially downwardly extending straight hook leg portion 61a.

Bend 63 is further provided with a knife portion 64 which is directed inwardly and towards the lower end 65 of hook member 61. This knife portion 64 may be made integral with hook member 61 and is preferably obtained by flattening or tapering hook member 61 at 66, whereby a knife projection 64 is created.

From Figs. 6 and 7 it is quite obvious that upon passing a tying string between bend 63 and portion 61a of the hook member 61, the string will be normally received on the lower end 65 of the hook member 61 for engagement therewith. Loop 62 is provided with an intermediate part which terminates in the free end 67 and extends in S-shaped formation between straight leg portion 61a and leg portion 68 with which said intermediate part forms two passageways or throats, respectively, a first passageway between 67 and 61a and a second passageway between 67 and 68. In order to disengage the string from hook member 61, the string can either be moved upwardly and intact through the passageway between portions 67, 61a, or it may enter the second passageway formed between the free end 67 and leg portion 68, so as to effectuate removal of the package string 12 from the hook member 61 by severing the string material at knife portion 64, which is directed toward said second passageway. Thus, the carrier device 60 will be disengaged from the string in two ways depending upon the purpose whether the package is to be kept intact and employed as a gift or for commercial use, which requires that the package and wrapper is to be opened and unpacked.

It is well understood that the knife projection 64, when struck out of the material of hook member 66, may also be provided with dents or such other means which will afford speedy severance of the string material.

As many possible embodiments may be made of the above invention, and as many changes might be made in the embodiments above set forth, it is to be understood that all matters hereinbefore disclosed or shown in the accompanying drawing are to be interpreted as illustrative and not in a limiting sense.

Having thus described the invention, what is claimed as new and desired to be secured by Letters Patent, is:

A carrier for parcels, packages and like articles, tied by means of a string element and comprising an elongated handle having a centrally disposed circular groove, a hook member engaging said groove and adapted to move in said groove about the horizontal axis of said handle, said hook member including a loop portion depending from said handle and terminating in a lower end for normally engaging said string element, said loop portion being provided with a substantially straight portion and with a leg portion substantially parallel to and spaced from said straight portion, a substantially S-shaped intermediate part integral with said loop portion extending in the space between said straight portion and said leg portion and providing with said latter portions two constricted passageways, first and second passageway, respectively, and a knife blade integral with said loop portion and directed toward said second passageway which is defined by said S-shaped intermediate part and said leg portion, whereby said string element when moved through said first passageway disengages intact from said loop portion and when guided through said second passageway will first be severed and then disengaged from said loop portion.

JOSEPH ALEXANDER.
